UNITED STATES PATENT OFFICE.

ROLLIN L. RODMAN, OF LOTT, TEXAS.

EMBROIDERING ATTACHMENT FOR SEWING-MACHINES.

No. 823,442.

Specification of Letters Patent.

Patented June 12, 1906.

Application filed April 21, 1905. Serial No. 256,737.

To all whom it may concern:

Be it known that I, ROLLIN L. RODMAN, a citizen of the United States, and a resident of Lott, in the county of Falls and State of 5 Texas, have invented a new and Improved Embroidering Attachment for Sewing-Machines, of which the following is a full, clear, and exact description.

My invention relates to attachments for 10 sewing-machines, and more particularly for those doing embroidery while the machine is operated by hand.

It consists in the various features and combinations hereinafter described and claimed.

Reference is to be had to the accompanying drawings, forming a part of this specification, in which similar characters of reference indicate corresponding parts in all the views.

Figure 1 is a perspective view of one embodiment of my invention shown in place upon a sewing-machine. Fig. 2 is an enlarged side elevation of the attachment. Figs. 3 and 4 are horizontal sections on the lines 3 3 and 4 4, respectively, of Fig. 2; and 25 Fig. 5 is a perspective view of the connector.

I have here illustrated a sewing-machine A having the usual needle-bar *a*, carrying the needle *b*, secured in place by the screw device *c*. Movable with the needle-bar is 30 the embroidering attachment B, which comprises a support 10, preferably in the form of a flattened tube. This support has at its lower extremity a lateral arm 11, having at its outer end an eye or socket 12, which may 35 be passed over the needle and raised against the lower extremity of the needle-bar. To secure the support in place upon the needle-bar, I have provided a connector C, preferably bent from an integral piece of wire and 40 having an angular portion 13 of such form and length as to adapt it to the particular conditions under which the attachment is to be used. This angular portion has at one extremity an eye 14, which may be passed 45 over the needle and brought into contact with the lower side of the socket 12, and an opposite eye 15 to surround some element movable with the needle-bar, conveniently the screw *c*. Each of these eyes may be furnished by one or more convolutions of the 50 wire.

Movable through the tubular support is a bar 16, having secured to its lower end a presser-foot 16^a, which may be formed of a 55 strip of metal similar to the bar, it being riv-

eted to one side thereof and then bent gradually to occupy a plane at right angles to that in which said bar lies, this bringing it parallel to the work-plate of the machine. In this horizontal portion of the presser-foot is an 60 opening in the form of a slot 16^b extending through the end of the foot farthest from the bar. At the upper extremity of the bar is an arm 17, and between this arm and an extension 18 of the arm 11 lies a spiral spring 19, 65 exerting its tension to draw the presser-foot normally downward, its movement in this direction being limited by the contact of the arm 17 with the top of the support.

The attachment is mounted upon the needle-bar of the machine upon which it is to be used, as has been above described, the form and size of the connector being such as to adapt it to the particular machine or the position in which the attachment is to operate 70 and so that it may move clear of all projecting portions of the machine-head. The silk or other embroidering material to be employed is now passed through the eye of the needle, this being accomplished without the 75 necessity for threading it through the presser-foot, since the slotted opening permits its introduction from the end. The work being placed upon the plate of the machine, it will be seen that when the needle is lowered by 80 turning the balance-wheel by hand it will begin the stitch and at the same time bring the presser-foot into coöperation with the upper face of the work and hold it firmly in place while the stitch is being completed. At 85 this time the movement of the bar through the support against the tension of the spring gives the desired yielding pressure. When the needle rises, the presser-foot moves with it, entirely releasing the work, so that it may 90 be turned or adjusted to the proper position for the next stitch.

Having thus described my invention, I claim as new and desire to secure by Letters Patent—

1. The combination with a sewing-machine having a needle-bar, of a tubular support, a lateral arm at the lower end of the support and provided with means for engaging the needle-bar, an extension on the arm, 100 a bar movable within the support, a slotted presser-foot on the bar, an arm on the upper end of the bar, and a spiral spring connecting the arm and the extension of the lateral arm.

2. The combination with a sewing-ma- 110

chine having a needle-bar, of a tubular support, a lateral arm at the lower end of the support and having an eye for engaging the needle, an extension on the arm, a connector 5 having an eye for engaging the needle beneath the lateral arm, means whereby said connector may be connected with the needle-bar, a bar movable within the support, a slotted presser-foot on the bar, an arm on the 10 upper end of the bar, and a spiral spring con-

necting the arm and the extension of the lateral arm.

In testimony whereof I have signed my name to this specification in the presence of two subscribing witnesses.

ROLLIN A. RODMAN.
